UNITED STATES PATENT OFFICE.

JOSEPH BERGER, JR., OF UTICA, NEW YORK, ASSIGNOR, BY MESNE ASSIGNMENTS, TO UNION SPECIAL MACHINE COMPANY, A CORPORATION OF ILLINOIS.

FEEDING MECHANISM FOR SEWING-MACHINES.

1,228,393.

Specification of Letters Patent.

Patented June 5, 1917.

Application filed August 4, 1902. Serial No. 118,236.

To all whom it may concern:

Be it known that I, JOSEPH BERGER, Jr., a citizen of the United States, residing in Utica, county of Oneida, and State of New York, have invented a new and useful Improvement in Feeding Mechanism for Sewing-Machines, of which the following is a description.

My invention relates to sewing machines of the type in which the binding and sewing are done simultaneously. Particularly, my invention relates to mechanism by which binding may be applied to all kinds of material, whether woven, knitted or otherwise produced, and in which the material and binding may be advanced to and fed from the stitch-forming mechanism simultaneously, evenly and without puckering or stretching the one relatively to the other.

My invention has been found specially useful in binding knit goods or loosely woven fabric, because such materials have a tendency to stretch excessively under the action of the feed and during the application of the binding, the latter being, usually, of close weave or texture and not so liable to stretch. With these conditions of the work it has been difficult to mechanically apply the binding evenly and smoothly and overcome the tendency of the material and binding to pucker relatively and produce unsightly work.

One of the objects of my invention is to provide a mechanism by which bindings may be applied to all kinds of fabric, with great facility, rapidity, accuracy and neatness; and by which the tendency of the material and binding to pucker relatively is overcome and prevented.

Another object of my invention is to provide means for controlling the condition of the material and binding as they are being fed to the stitch-forming mechanism; that is to say, operating upon the two, or manipulating them, in such manner as to produce precisely the condition desired at the stitch making point, thus rendering it possible for the operator to produce and maintain evenness of work during the rapid operation of the machine.

It is a further object of my invention to so enlarge the scope and operation of machines of the character stated as to enable them to perform, under the control of the operator, certain kinds of work, such as full-

ing one piece of work on or relatively to another, or stretching one piece of work on or relatively to another. Also to produce a combination of stitch-forming, feeding and presser-foot mechanisms which is capable of producing the results stated.

Other objects will be set forth in the body of the description.

My invention consists in the parts, features and combinations herein described and claimed and upon which I have endeavored to lay stress by particular reference.

The essential features of my machine, combination or mechanism embrace a stitch-forming mechanism of any desirable character, a feeding mechanism involving the principles and having the features hereafter specified, and a presser-foot mechanism capable of performing the functions and of being manipulated as presently described. In some instances a binding guide of suitable conventional form may be properly located with respect to the stitch-forming, feeding and presser-foot mechanisms.

In the drawings I have illustrated a chain-stitch machine having the several features noted and portraying my invention in a form capable of attaining good results, and therein:

Figure 1 is a perspective view of a machine having my invention applied thereto; Fig. 2 is a plan view of a detail showing the feeding mechanism; Fig. 3 is a sectional elevation on the line $x-x$ of Fig. 2; Fig. 4 is a similar view on the line $x'-x'$ Fig. 2; Fig. 5 is a view similar to Fig. 3 showing another form of my feeding mechanism; Fig. 6 is a side elevation of the presser-foot; Fig. 7 is a vertical section of the presser-foot on the line $v-v$ of Fig. 6; Fig. 8 is a plan of a section of the throat-plate, showing a certain arrangement of the feed-dogs; Fig. 8^a is a similar view showing another arrangement of the feed-dogs also showing in dotted lines the relative arrangement of the binder to these feed dogs, and the binding strip and body fabric; Fig. 9 is a rear elevation of the overhanging arm and head of the machine, showing the presser-foot lifting means; and Fig. 10 is a plan showing the binding guide and tension.

The overhanging arm of the machine is indicated by A; and B, is the bed-plate; C, the work-plate; D, the needle actuating lever; D', the needle-bar; d, the needle; E,

the driving wheel on the main-shaft; A', the usual spring controlled presser-bar; H, the presser-foot; h, the screw for holding the foot to the bar; and G, the throat-plate.

5 The presser-foot is shown as composed of the main part H, having three, parallel, vertical bores extending from the bottom upwardly, and the central one of which extends through the top of the part H, by a 10 narrowed or confined extension. The part H, also carries a foot-portion 12, which may be integral therewith or secured thereto in any suitable manner. A second foot-portion 13, not so extensive as the portion 12, is 15 provided with vertical pins 13^a, 13^a, and 13^b, seated and sliding freely in respective bores of the main part H, and the central one 13^b, being longer than the others and operating in the extension of the central 20 bore. This central pin is surrounded by a coiled spring 14, housed in the enlarged portion of the central bore, and said pin, at its upper end, is notched, grooved or cut away so as to provide a seat, between, 25 two shoulders, for the reception of a screw or pin 13^c, which limits its vertical movement and prevents the second foot 13 falling from the part H, when the latter is lifted to relieve the work from all pressure.

30 The spring 14, constantly tends to press the foot 13, toward the work and affords a yielding pressure when the said foot is alone pressing upon the work. When the foot 13, is forced, against the spring, to its highest 35 extent, the screw or pin 13^c, constitutes a stop producing a condition which renders all the parts of the foot rigid and practically solid. The two end pins 13^a, act as guides to prevent the foot 13, from turning 40 relatively to the foot 12, and keep the two in proper relation laterally. A lever 15, pivoted to the arm A, is operatively connected with the presser-bar so as to lift the latter during the operation of the machine, 45 any means desirable being provided for actuating the lever, such as a treadle 15^a having connection 15^b with said lever. It will thus be seen that, during the operation of the machine, the presser-foot can be raised 50 or lowered at will to any desired extent.

A suitable form of binding-guide is shown in Figs. 1 and 10, the same being suitably secured to the cloth-plate by a screw and extended to a position just in advance of 55 and beside the supplemental foot 13. The guide consists of a base-plate 16, a turning or folding guide 17, for the binding-strip 18, and a tension device for the strip 18, comprising a rigid piece 19, a spring-strip 60 20, bearing thereon, a slotted holding piece 22, for confining the bent end 21, of the strip 20, and an adjusting-screw 23, passing through the holding piece 22, and pressing upon the strip 20, to regulate the pressure thereof on the binding strip 18. Being

secured by a screw, by loosening the latter the binding-guide may be swung aside for free access to the stitching mechanism and for properly inserting the binding strip therein. This binding guide 17 is of the type known 70 as an English binder, the delivery end being formed at an angle to the line of feed, the material being fed into the binder at right angles to the direction of feed and by the angular form of the delivery end a reverse fold is given the binding as it leaves the binder, the delivery end being located alongside the front presser portion of the presser foot, and in front of the rear portion of said foot.

75 The feeding mechanism devised for co-operating with the stitch-forming mechanism, the presser-foot and binding guide, is so constructed as to feed the body fabric or material fast or slow relatively to the feed of the binding material, or to feed the binding material fast or slow relatively to the body-material, this depending entirely upon the character of the materials operated 80 upon or the particular effect desired.

85 One form of my invention is shown in Figs. 2, 3 and 4, in which F, is the rocking-frame, pivoted to the bed-plate B, of the machine, such frame deriving its movements through any suitable connection with the 90 driving shaft. The feed-bar F', horizontally disposed, is pivoted, or journaled at its rear end to the upper end of the rocking frame, at a; and at its forward end said bar has suitably secured thereto a feed-dog 100 F'', the horizontal portion of which is provided with teeth, as usual. On its under side, the feed-bar is provided with an angular piece between which and the body of the bar an actuating eccentric or cam on 105 the driving shaft is embraced for imparting vertical movements. Between its ends, the rocking-frame has secured thereto, in any suitable manner, a bracket-piece carrying a vertically disposed bar 1, provided 110 with a number of perforations 1^a, for the reception of a screw carried by one end of an adjustable link 7, having its opposite end adjustably secured in like manner in any one of a series of perforations 2^a, in a 115 similar bar 2, suitably secured to a second feed-bar 3, supported and guided in bearings 4, carried by the main feed-bar F'. The second feed-bar is free to slide longitudinally on the main feed-bar and independently thereof, but is confined by its guides so as to partake of the vertical movements of the feed-bar F'; the second bar, at its forward end, carries a feed-dog 6, having on its horizontal portion teeth 5. 120 The link 7, forms the driving connection 125 between the rocking-frame F, and the second bar 3, and as said link is adjustable on the bars 1 and 2, the amount of movement transmitted from the rocking frame to the 130

second feed-bar can be regulated and varied according to the character of work to be performed or the results desired. Obviously, the movement of the second dog can be caused to feed fast or slow according to the position of the link 7, along the bars 1 and 2, and that said movement may be in excess of the movement of the feed-bar F', by placing the link 7, above the pivotal connection of the rocking-frame with the bar F' as shown in Fig. 4, or may be the same as, or as much less than, the movement of said bar F', as desired, by adjusting said link 7, along said bars 1 and 2,—see Fig. 3.

Another form of my invention is shown in Fig. 5, in which the second bar 3, is secured to the main-bar F', on the opposite side of the latter, by means of screws 3^a, passing through long slots in the second bar and by which means the latter is guided in its movements on and is secured to the bar F'. The dog 5, in this form of my invention is made integral with the second bar 3. The actuating means in this form of my invention consists of a lever 2, extending above the main feed-bar, and longitudinally slotted, pivoted at 9^a, to a lug 9, carried by the bed-plate, said lever 2, being pivoted to the second bar 3, by means of a screw 11, entering the same after passing through the slot in lever 2. Motion is imparted to the lever 2, by means of a link 7, pivotally connected at one end to the upper end of the rocking-frame F, and at its other end pivotally and adjustably connected to the lever 2, by means of a screw 10, passing through the end of link 7, and entering the slot in lever 2. By this connection it will be clear that the second feed-bar may be caused to move faster than the bar F', or move with the same or lesser speed, according to the adjustment of the link 7, in the slot of lever 2.

It will be clear from the above description that the speed of the two feed-dogs may be changed relatively, and that the dog 5 may be caused to move faster or slower than the dog f, this depending upon the character of the work to be performed, or the results desired, or the necessities of the conditions caused by the character of the work operated upon. Moreover, it will be clear that as the link 7, is moved down the bars 1, 2, the dog 5, if bar 2, is secured thereto at a right-angle, will be maintained in the same position relatively to the needle. This is not always desirable and is undesirable in certain conditions and in operating upon certain kinds of work, such as in feeding edgings of open-work character, or in bar stitching, when it becomes necessary to have the feed-dog operate closely to the needle as possible. To provide for this, the bar 2, may be secured to the second feed-bar 3, at an inclination, or obtuse angle,

in which case as the link is lowered along the bars 1 and 2, the dog 5, will be moved toward the needle, as clearly shown in Fig. 4, thus enabling said dog to work close to the needle and engage the edging and advance the same with certainty. 70

The feed-dogs may be of any desired shape and size and may have any desired relation to each other, such shape and relation depending entirely upon the character 75 of work operated upon or the results or effects desired. In Fig. 8, the main-dog 24, is shown broad and extending to the outer edge of the supplemental dog 25, the latter being narrow and lying in front of the main 80 dog. In Fig. 8^a, the dog f, is shown narrow and long, and the dog 5, much shorter than the dog f and lying in a plane parallel with the latter but in front thereof. The feed dogs when arranged as shown in this 85 Fig. 8^a, are especially adapted for binding an elastic body fabric. The binder is positioned relative to the needle, so as to be located immediately in front of the feed dog 5, which operates on the binding strip 90 in rear of the needle, and it is also arranged alongside of the auxiliary feed dog f, as shown in Fig. 1, and as referred to above.

By this arrangement of the feed dogs and binder, the auxiliary feed dog f may be 95 moved faster than the main feed dog 5 and caused to full the elastic material sufficiently to prevent any undue stretching thereof. Inasmuch as this feed dog has a surface in engagement with the fabric during the 100 feeding movement, which extends from a point substantially in a line at right angles to the feed and passing through the path of the needle to a point in advance of the needle, the body material is gathered and 105 held in gathered position until it is caught and stitched to the binding by the stitching mechanism.

Then again, this locating of the binder directly in front of the stitching mechanism 110 and alongside of the auxiliary feed dog f, permits the stitching of the binding on to a curved edge, as the fabric can be readily turned.

The particular shapes and arrangements 115 herein shown are merely illustrative of modes of carrying out the spirit of my invention and are not intended, in any sense, as limitations; for it will be clear that many changes in shapes and arrangement of parts 120 can be made without departing from the principles of my invention.

From the above description and the illustrations afforded by the drawings, it will be clear that adjustments may be made to cause 125 the forward dog to feed either faster or slower than the rear dog; or the latter may be given a speed of travel the same as the forward dog or faster or slower than the latter. The relative speed of the dogs de- 130

pends upon the character of work operated upon; and this is true also of the size and shape of the dogs and the relative disposition thereof. For example, in binding a garment, or sewing edging to fabric, around curved edges, it is important to feed the binding or edging faster than the garment or fabric so as to produce neat, smooth work and avoid puckering the one relatively to the other. Moreover, after the speed of the two feed-bars has been adjusted relatively, with *e. g.* the main bar moving faster than the auxiliary bar, it may be necessary or desirable to cause that portion of the work which is being fed the faster to be momentarily retarded or its movement practically suspended. This may be accomplished by depressing the lever 15, and slightly lifting the presser-bar and, consequently, the foot 12, from the work, the spring 14, holding the foot 13, down upon the work. This results in continuing the feed of the work or binding under foot 13, because the action of the feed thereunder receives coöperation from said foot 13. Not so, however, with foot 12; for, it being raised from the work, the feed thereunder receives no coöperation therefrom and the feed has little or no effect upon the work. This action which renders the differential feeding movement of the advanced feeding ineffective may be produced and repeated at the will of the operator and without stopping the stitch-forming mechanism, as the movement of the lever is under his control. This may become important in operating upon, or placing bindings upon the edges of, loosely woven materials. Moreover, this function may be accomplished when the feed of both dogs is the same, the foot 12 being raised resulting in retarding the movement of the work operated upon by the dog thereunder.

One or more needles and complementary stitch forming mechanisms may be used in connection with the feeding mechanism of my invention.

Another use of my invention is in fulling or shirring one piece of work on or relatively to another, this being accomplished by feeding the piece to be fulled or shirred faster than the other; or one piece of work may be stretched on or relatively to the other by causing one feed to move slower than the other. In fact, there is no end to the variety and character of effects and results that can be produced by regulating the speed of the feed-dogs relatively and properly manipulating the presser-feet.

For the sake of clearness in terminology and for convenience, I denominate in the claims the forward feed dog, or that which engages the goods in advance of the needle, as the auxiliary feed dog, and the rear feed dog, or that which engages the goods and feeds them away after the stitching has been

performed, as the main feed dog, and call the respective supporting bars therefor auxiliary and main feed bars.

Having thus described my invention what I claim and desire to secure by Letters Patent is:

1. A sewing and binding machine comprising feeding mechanism, including a device operating upon and feeding the body fabric in advance of and on one side of the stitching point, and a feeding device operating upon and feeding the binding in rear of the stitching point, a binding mechanism coöperating with the feeding mechanism, mechanism coöperating with the feeding mechanism, comprising a plurality of parallel members engaging the upper face of the fabric arranged one beside the other and coöperating with the respective feeding devices, means for imparting a differential movement to said feeding devices, and means for rendering ineffective said differential feed movement without stopping the stitch forming mechanism. 75

2. A sewing and binding machine comprising a feeding mechanism having a plurality of dogs operating at different speeds the one upon the fabric in advance of the needle and the other upon the binding strip in rear of the needle, a presser foot having portions coöperating respectively with the several dogs arranged side by side and one portion extending in advance of the other, means for rendering ineffective the differential movement of the feed dogs without stopping the stitch forming mechanism, and a binding guide coöperating with the feeding mechanism. 90

3. A sewing and binding machine comprising a differential feed mechanism, having a plurality of feeding devices operating one upon the body fabric in advance of and to one side of the stitching point, the other upon the binding in rear of the stitching point, a presser foot having parallel portions coöperating respectively with the several feeding devices, the one which coöperates with the first mentioned feeding device extending from a point in rear of and to one side of the needle to a point in front thereof, and the other located with its front end in rear of the front end of the first foot portion, and a binding guide for guiding and applying a binding to the work, the delivery end thereof being positioned alongside of said first portion and in front of the rear portion, and means for varying the effective differential action of the feeding mechanism without stopping the stitch forming mechanism. 110

4. A sewing and binding machine comprising a differential feed mechanism having a plurality of feeding devices operating, one upon the body fabric in advance of the needle and extending up to the needle 115

to crowd the goods thereto, the other operating upon the binding in rear of the stitching point, a presser foot having two independently operating portions, one co-operating with the forward feeding device, but also bearing upon the fabric at a point in rear of the needle, and the other a spring pressed portion co-operating with the rear feeding device but extending in front of the needle, a binding guide with its delivery end located alongside the front presser foot and in front of the rear foot, and means for varying the effective differential action of the feeding mechanism without stopping the stitch-forming mechanism.

5. A sewing and binding machine comprising a differential feeding mechanism having a plurality of feeding devices operating one upon the body fabric in advance of the needle and extending up to the needle to crowd the goods thereto, the other operating upon the binding in rear of the stitching point, a co-operating presser foot mechanism, a binding guide arranged at right angles to the line of feed and arranged with its delivery end cut off at an angle and delivering the binding with a reverse fold to the stitch-forming mechanism and treadle-controlled means for varying the effective action of the differential feeding mechanism.

6. A sewing and binding machine comprising a differential feeding mechanism having a plurality of feeding devices, one operating upon the body fabric in advance of the needle and extending up to the needle to crowd the goods thereto, the other operating upon the binding in rear of the stitching point, a presser foot having two portions, one portion co-operating with the forward feeding device and the other portion co-operating with the rear feeding device, a binding guide with its delivery end cut off at an angle to the line of feed and feeding the binding with a reverse fold, and with said delivery end alongside the front portion of the presser foot and in front of the rear portion of said foot and treadle-controlled means for varying the effective action of the differential feeding mechanism.

7. A sewing and binding machine comprising feeding mechanism, including a device operating upon and feeding the body fabric in advance of and on one side of the stitching point, and a feeding device operating upon and feeding the binding in rear of the stitching point, a binding mechanism co-operating with the feeding mechanism, mechanism co-operating with the feeding mechanism, comprising a plurality of parallel members engaging the upper face of the fabric arranged one beside the other and co-operating with the respective feeding devices, means for imparting a differential movement to said feeding devices, and treadle operated means for rendering in-

effective said differential movement without stopping the stitch forming mechanism.

8. A sewing machine including in combination a needle, complemental stitch forming mechanism, and a feeding mechanism including an auxiliary feed dog located at one side of the needle and having its surface in engagement with the fabric extending from a point substantially in a line at right angles to the feed and passing through the path of the needle to a point in advance of the needle, a main feed dog engaging the material in rear of the needle, means for reciprocating the main feed dog, means for giving said auxiliary feed dog a differential movement relative to the main feed dog, a presser foot mechanism, and means for rendering the differential feeding movement of the auxiliary feed dog ineffective, without stopping the stitch forming mechanism.

9. A sewing machine including in combination, a needle, a binder located on one side of the needle for guiding the binding strip, a feeding mechanism including a main feed dog engaging the body fabric and binding strip in rear of the needle, an auxiliary feed dog located on the opposite side of the needle from the binder and having its surface in engagement with the fabric extending from a point lying substantially in a line at right angles to the feed and passing through the needle path to a point in advance of the needle and engaging only the body fabric, means for reciprocating the main feed dog, means for giving the auxiliary feed dog a differential movement relative to the main feed dog, and means for rendering the differential feeding movement of the auxiliary feed dog ineffective, without stopping the stitch forming mechanism.

10. A sewing and binding machine comprising a differential feed mechanism, having a plurality of feeding devices operating one upon the body fabric in advance of and to one side of the stitching point, the other upon the binding in rear of the stitching point, a presser foot having parallel portions co-operating respectively with the several feeding devices, the one which co-operates with the first mentioned feeding device having its surface in engagement with the fabric extending from a point in rear of and to one side of the needle to a point in front thereof, and the other located with its front end in rear of the front end of the first foot portion, and a binding guide having its longitudinal axis located substantially at right angles to the line of feed for folding and reversing the binding strip, said binding guide being positioned between the needle and the forward end of the auxiliary feed dog, whereby the body fabric is free from contact with the binding strip when engaged by the forward end of said auxiliary feed dog.

11. In a sewing machine, the combination of a needle, and a feeding mechanism including an auxiliary feed dog and a main feed dog disposed so as to engage the under face of the fabric and feed the same to the needle, said feed dogs being arranged in parallel planes and one in advance of the other, means for giving the auxiliary feed dog a differential movement relative to the main feed dog, said auxiliary feed dog having its surface in engagement with the fabric extending from in front of the needle to a point substantially in a line at right angles to the line of feed, and passing through the path of the needle, and a presser mechanism coöperating with said feeding mechanism including spring-pressed opposing members coöperating respectively with the feeding members, the spring-pressed opposing member coöperating with the auxiliary feed dog extending to a point in advance of the other opposing member, and a binder for guiding a binding strip to the main feed dog, said binder being located in front of one of said opposing members and alongside of the other opposing member.

12. A feeding and binding mechanism for sewing machines, including stitch-forming mechanism and a feeding mechanism, said feeding mechanism including a feed dog for engaging the material in rear of the needle, a feed dog for engaging only the body fabric in advance of the needle, means for giving said feed dog engaging the body fabric in advance of the needle a differential movement relative to the other feed dog, said feed dog in advance of the needle having the surface in engagement with the fabric extending rearwardly substantially to a line at right angles to the line of feed and cutting the forward end of the rear feed dog, a presser foot mechanism coöperating with said feed dog, and a binding guide for directing a binding strip to the stitching mechanism.

13. A feeding and binding mechanism for sewing machines, including stitch-forming mechanism and a feeding mechanism, said feeding mechanism including a feed dog for engaging the material in rear of the needle, a feed dog for engaging only the body fabric in advance of the needle, means for giving said feed dog engaging the body fabric in advance of the needle a differential movement relative to the other feed dog, said feed dog in advance of the needle having the surface in engagement with the fabric extending rearwardly substantially to a line at right angles to the line of feed and cutting the forward end of the rear feed dog, a presser foot mechanism coöperating with said feed dog, a binding guide for directing a binding strip to the stitching mechanism, and treadle-operated means for controlling the coöperative action

of the feed dogs and the presser foot mechanism.

14. A sewing and binding machine comprising a differential feeding mechanism having a plurality of feeding devices providing fabric-engaging surfaces, one engaging the body fabric in advance and at one side of the stitching point, and also substantially in advance of a line at right angles to the travel of the feeding mechanism and passing through the path of the needle, the other engaging the binding in rear of the stitching point, a presser foot having a surface coöperating with the first mentioned feeding device and extending forward of the needle and on one side thereof, and having another surface coöperating with the second feeding device, with its front end in rear of the front of the first foot surface, and a binding guide for guiding and applying a binding to the work, the delivery end thereof being positioned alongside of said first foot surface, and in front of the rear foot surface.

15. A sewing and binding machine comprising a differential feed mechanism having a plurality of feeding devices operating, one upon the body fabric in advance of and to one side of the stitching point, the other upon the binding in rear of the stitching point, a presser foot having a surface coöperating with the first mentioned feeding device and extending forward of the needle and on one side thereof, and having another surface coöperating with the second feeding device with its front end in rear of the front of the first foot surface, and a binding guide having its longitudinal axis located substantially at right angles to the line of feed for folding and reversing the binding strip, said binding guide being positioned between the needle and the forward end of the first feeding device, whereby the body fabric is free from contact with the binding strip when engaged by the forward end of said feeding device.

16. In combination, stitch-forming mechanism; feeding mechanism, including a main and an auxiliary dog; a presser-foot mechanism including a bar carrying a main and an auxiliary foot, and a device for controlling the latter independently of the main foot; and treadle-operated controlling means coöperating with said presser-foot mechanism whereby when the main foot is raised from one of the feed-dogs, said device becomes active to maintain the auxiliary foot in coöperation with the other feed-dog.

17. In combination, a stitch-forming mechanism; a feeding mechanism; a presser-foot mechanism, including a main and an auxiliary foot, and a device for controlling the latter independently of the main foot; and treadle-operated controlling means, operable during the running of the machine, for moving the main foot from coöperation with the

feed and for permitting said device to become active to maintain the auxiliary foot yieldingly in coöperation with the feed.

18. In combination, a feeding mechanism, comprising two independently movable dogs; a presser-foot mechanism comprising a bar carrying two independently movable feet; and treadle-operated means for controlling the coöperative action of the dogs and feet on the work whereby the latter may be either fulled or stretched.

19. In combination, a feeding mechanism comprising two relatively movable dogs, co-operating presser foot mechanism, means for causing the movement of the dogs to be relatively different, and treadle-operated means for controlling the coöperative action of the dogs and presser foot mechanism on the work, whereby the latter may be either fulled or stretched.

20. In combination, a feeding mechanism, comprising two relatively movable dogs; a presser-foot mechanism, comprising a bar carrying two relatively movable feet; means for causing the movement of the dogs to be relatively different; and treadle operated means for controlling the coöperative action of the dogs and feet on the work, whereby the latter may be either fulled or stretched.

21. In combination, a presser-bar carrying a presser-foot, comprising a main part having a plurality of bores; an auxiliary foot having a plurality of pins sliding in said bores; and means for normally depressing said auxiliary foot below said main foot.

22. In combination, a presser-bar carrying a presser-foot, comprising a main part having a plurality of bores; an auxiliary foot having a plurality of pins sliding in said bores; means for normally depressing said auxiliary foot below said main foot and for limiting the movement of the former relatively to the latter.

23. In combination, a presser-bar carrying a presser-foot, comprising a main part having a plurality of bores, an auxiliary foot having a plurality of pins sliding in said bores; a spring surrounding one of said pins and normally depressing said auxiliary foot, and means for limiting the movements of the auxiliary foot relatively to the main foot.

24. A sewing machine, including in combination a work support, a stitch forming mechanism and a feeding mechanism, comprising a main feed bar, an auxiliary feed bar arranged in parallelism with said main feed bar, means for simultaneously raising and lowering the said feed bars, means for giving said main feed bar a fabric feeding movement, means for giving said auxiliary feed bar a differential feeding movement, a feed dog carried by said main feed bar, a fabric engaging device carried by said aux-

iliary feed bar, independent presser members coöperating respectively with said feed dog and said fabric engaging device, and a manually operated device located beneath the work support and under the control of the operator for controlling the effective differential feeding movement of the fabric engaging device without stopping the action of the stitch forming mechanism.

25. A sewing machine, including a work support, a stitch forming mechanism and a feeding mechanism, comprising a main feed bar and an auxiliary feed bar arranged in parallelism therewith, said feed bar being disposed beneath the work support, a main feed dog carried by the main feed bar and arranged to engage the fabric in the rear of the stitch forming mechanism, a fabric engaging device carried by the auxiliary feed bar and arranged to engage the fabric in advance of the stitching point, means for simultaneously raising and lowering said feed bars, means for imparting a fabric feeding movement to the main feed bar, means for giving said fabric engaging device a differential feeding movement relative to said main feed dog, independent presser members coöperating respectively with the main feed dog and the said fabric engaging device, said presser member coöperating with the fabric engaging device extending in advance of the presser member coöperating with the feed dog, a manually operated device located beneath the work support and under the control of the operator for raising the presser member coöperating with the fabric engaging device without disturbing the coöperative action of the presser member coöperating with the main feed dog.

26. A sewing and binding machine, including a work support, a stitch forming mechanism, a feeding mechanism comprising a main feed bar and an auxiliary feed bar arranged in parallelism therewith, said feed bars being disposed beneath the work support, a main feed dog carried by the main feed bar and arranged to engage the binding in the rear of the stitching point, a fabric engaging device carried by the auxiliary feed bar and arranged to engage the body fabric in advance of the stitching point, means for simultaneously raising and lowering said feed bars, means for imparting a fabric feeding movement to the main feed bar, means for giving said fabric engaging device a differential feeding movement relative to said main feed dog, independent presser members coöperating respectively with the main feed dog and the said fabric engaging device, said presser member coöperating with the fabric engaging device extending in advance of the presser member coöperating with the feed dog, a manually operated device located be-

neath the work support and under the control of the operator for controlling the effective differential feeding movement of the fabric engaging device without stopping the stitch forming mechanism, and a binding 5 guide for guiding and applying a binding to the body fabric, said binding guide having its longitudinal axis substantially at right angles to the line of feed, whereby 10 the binding strip is inverted as it is led to the stitching mechanism, the delivery end of said binding guide being located in front of the presser member coöperating with the main feed dog and along the side of the 15 presser member coöperating with the fabric engaging device.

27. A differential feeding mechanism including in combination, a rocking frame, means for rocking said frame, a main feed dog, a main feed bar pivoted directly to said rocking frame and supporting said main feed dog, means for raising and lowering said main feed bar, an auxiliary feed bar, a feed dog carried thereby, means for slidingly supporting said auxiliary bar on said main feed bar whereby said auxiliary bar is raised and lowered with said main feed bar, and means for positively moving said auxiliary feed bar back and forth from substantially the same point of connection with the rocking frame as the main feed bar, including devices for giving said auxiliary feed dog differential movements relative to the main feed dog.

35 28. A sewing machine including in combination a bed plate, a rocking frame pivoted thereto, and extending upwardly above said bed plate, a main feed bar pivoted to said rocking frame, a feed dog carried by said 40 main feed bar, an auxiliary feed bar, means for slidingly supporting said auxiliary feed bar on said main feed bar, means for raising and lowering said main feed bar, and said auxiliary feed bar, means for moving said auxiliary feed bar back and forth including a lever pivotally supported by the bed plate and extending upwardly therefrom, means for connecting said lever to said auxiliary feed bar, a link bodily movable in unison with the main feed bar, and having a shiftable connection with said lever.

29. A sewing machine including in combination, a bed plate, a rocking frame pivoted thereto and extending upwardly above said bed plate, a main feed bar pivoted to said rocking frame, a feed dog carried by said main feed bar, an auxiliary feed bar, means for slidingly supporting said auxiliary feed bar on said main feed bar, means for raising and lowering said main feed bar and said auxiliary feed bar, means for moving said auxiliary feed bar back and forth including a lever pivoted to the bed plate 55 and extending upwardly therefrom, means

for connecting said lever to said auxiliary feed bar, and a link pivotally connected to said lever and to the same point of connection with the rocking frame as the main feed bar.

30. A cloth-feeding mechanism having, in combination, a device for engaging the bottom of the work; a presser-foot coöperating with said device, a device for engaging the top of the work in a path beside and parallel with said first device, means for giving said devices relative action, and a treadle-operated controlling means coöperating with one of said devices for manipulating the same, at the will of the operator, to change its action on the work.

31. A cloth-feeding mechanism having, in combination, a device for engaging the bottom of the work, means for actuating said device so as to give it differential action on the work, a device for engaging the top of the work, and a treadle-operated controlling means coöperating with one of said devices for manipulating the same, at the will of the operator, to change its action on the work.

32. In combination, a stitch-forming mechanism, a feeding mechanism for moving the work past the stitch-forming mechanism, an auxiliary mechanism coöperating with the feeding mechanism for engaging and controlling the work, a presser foot mechanism coöperating with the said feeding mechanism and the said auxiliary mechanism, and treadle-operated controlling mechanism, coöperating with one of said mechanisms, for modifying the action of the feeding and auxiliary mechanisms on the work, said controlling mechanism being accessible presented to the operator to be actuated by the latter at will.

33. In combination, a stitch-forming mechanism, a feeding mechanism, including a main and an auxiliary feed dog, and means for imparting to said dogs differential movements including a rocking-frame and connections therefrom to said dogs, a presser foot mechanism coöperating with the dogs of said feeding mechanism, and a treadle-operated controlling mechanism coöperating with one of said mechanisms for modifying the normal action thereof, whereby the hands of the operator will be free and he may control the functions of the machine during the running of the latter and without affecting the stitch formation.

34. In combination, a stitch-forming mechanism, a feeding mechanism, including a main and an auxiliary feed-dog relatively movable, a presser-foot mechanism, including two work-engaging devices, and means coöperating with one of said devices whereby its action will be different from the other, a controlling mechanism coöperating with said presser foot mechanism for actuating the latter so as to modify the action of the

said dogs and devices upon the work, said controlling mechanism being accessibly presented to the operator to be actuated by the latter at will, whereby the hands of the operator will be free and he may control the functions of the machine during the running of the latter and without affecting the stitch-formation.

35. In combination, a stitch-forming mechanism, a feeding mechanism, including a main and an auxiliary dog, a presser foot mechanism including two feet movable relatively, means for causing the movement of the dogs to be relatively different including 10 a rocking-frame and independent connections therefrom to the respective dogs, controlling means coöperating with one of said mechanisms for modifying the action of both said mechanisms on the work, and treadle-operated means located below the work plate of the machine and connected with the controlling means, whereby the character of the work may be changed at will during the running of the machine and both hands of 15 the operator will be left free to handle the work.

36. In combination, a stitch-forming mechanism, a feeding mechanism including a main and an auxiliary dog, a presser foot mechanism including two work-engaging devices, means for causing the movements of the dogs to be relatively different, and controlling means, operable during the running of the machine, and coöperating with the 20 presser foot mechanism for causing the lat- 25

ter to change the action of the feeding mechanism on the work.

37. In combination, a stitch-forming mechanism, a feeding mechanism including a main and an auxiliary dog, the said feeding mechanism including means confining it to movements for feeding the work in one direction only, a presser-foot mechanism including two work-engaging devices, means for causing the movements of the dogs to be relatively different, controlling means co-operating with one of said mechanisms for modifying the action of the feeding mechanism on the work, and treadle-operated means located below the work-plate of the machine and connected with the controlling means, whereby the character of the work may be changed at will during the running of the machine and both hands of the operator will be left free to handle the work. 30 35

38. In a feeding mechanism, the combination of a main and an auxiliary feed bar, means for actuating said feed bars for imparting the feed movements thereto including a rocking frame directly connected to 40 one of said feed bars and a lever mechanism connecting said rocking frame and the other feed bar, and means for regulating the action of the feeding mechanism whereby either feed bar may be caused to travel faster 45 than the other. 50 55
